UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A BASE FOR LAMPS.

SPECIFICATION forming part of Design No. 23,417, dated July 3, 1894.

Application filed May 21, 1894. Serial No. 512,010. Term of patent 3½ years.

To all whom it may concern:

Be it known that I, LOTHAR VON GRAVE, a subject of the Emperor of Germany, residing at Wallingford, New Haven county, State of Connecticut, have invented and produced a new and original Design for a Base for Lamps, &c., of which the following is a specification, reference being had to the accompanying drawings, in which—

The essential characteristics of my design consist of an ornamental base, the body of which is rectangular in form and has ornamental panels with the representations of allegorical figures in the foreground.

In the drawings a represents the body of the base which is rectangular in form and has ornamental panels b thereon, in the foreground of which is the representation of allegorical figures c. Feet for the base is formed by mask-like extensions d projecting therefrom.

What I claim is—

The design for a base for lamps, &c., substantially as shown and described.

LOTHAR VON GRAVE.
